Patented Feb. 25, 1913.

UNITED STATES PATENT OFFICE

ALFRED LEONARD STROBERG, OF BROCKTON, MASSACHUSETTS.

COLLAPSIBLE LAST.

1,054,471.

Specification of Letters Patent. Patented Feb. 25, 1913.

Application filed August 24, 1912. Serial No. 716,853.

To all whom it may concern:

Be it known that I, ALFRED LEONARD STROBERG, a citizen of the United States, residing at Brockton, in the county of Plymouth and State of Massachusetts, have invented certain new and useful Improvements in Collapsible Lasts, of which the following is a specification.

This invention relates to a last comprising 10 a heel-part and a forepart hinged together to permit a relative swinging movement of said parts, for the purpose of longitudinally contracting or collapsing and extending the last, the last also including a detachable instep block seated on the forepart.

The invention has for its object, first, to enable the detachable block to act as a strut to prevent relative contracting movements of the forepart and heel-part when the last 20 is in condition for use.

The invention also has for its object to provide improved means for detachably locking the block in position to act as a strut.

25 The invention consists in the improvements which I will now proceed to describe and claim.

Of the accompanying drawings, forming a part of this specification, Figure 1 represents a side elevation of a last embodying my invention, the block being detached from the heel and foreparts. Fig. 2 represents a top plan view of a portion of the last, showing the parts operatively assembled. Fig. 3 represents a section on line 3—3 of Fig. 2. Fig. 4 represents a side view of an implement which may be used to release the instep block.

The same reference characters indicate the 40 same parts in all of the figures.

In the drawings, 12 represents the heel-part of my improved last, the same having at its forward end a recessed bearing face 13, and a substantially flat abutment located 45 above and overhanging the face 13. In the forward end portion of the heel-part is formed a vertical kerf 15 which opens into the crown of the heel-part and into the abutment 14.

50 16 represents the forepart, which is cut away at its upper portion to form a block seat 17, and has a salient rear end face 18 which merges into the seat 17 and is formed to fit the recessed face 13 of the heel-part.

55 The forepart 16 is provided with a kerf 19

which registers with the kerf 15 and opens into the seat 17 and salient rear face 18.

20 represents a hinge-plate which is attached to the heel-part within the kerf 15 by transverse pins or rivets 21, and projects 60 forward from the heel-part into the kerf 19 of the forepart.

22 represents a pivot pin which connects the projecting portion of the hinge-plate 20 with the forepart 16. The faces 13 and 18 65 and the rear portion of the block seat 17 are formed as indicated by Fig. 1, to permit relative swinging movements of the heel and foreparts for the purpose of longitudinally contracting the last, as indicated by 70 dotted lines in Fig. 1, and longitudinally extending the last, as indicated by full lines. The locking-plate 20 is provided with a locking shoulder 23, adapted to engage a complementary shoulder on a locking-plate on the 75 instep block, as hereinafter described.

24 represents the instep block, which is entirely detachable from the above-described parts, and has a bottom face 25 formed to fit the seat 17, and a rear face 26 formed to 80 bear on the abutment 14, when the last is extended. The block is provided at its rear end portion with a vertical kerf 27, which opens through the bottom face 25 and end face 26, and registers with the kerf 15 in the 85 heel-part, and the kerf 19 in the fore-part.

28 represents a locking plate which is pivoted to the block 24 within the kerf 27, and has a projecting portion 28^a adapted to enter the kerf 15 in the heel-part, and another projecting portion 28^b adapted to 90 enter the kerf 19 in the forepart. The locking-plate is also provided with a locking shoulder 30, adapted to engage the shoulder 23 of the hinge plate 20, as shown by Fig. 3. 95

The spring 31 normally holds the locking-plate 28 in the position shown by Figs. 1 and 3, the shoulder 30 being thus adapted to spring into engagement with the shoulder 23. The projection of the shoulder 30 by 100 the spring 31 is limited by a stop 32 (Fig. 3) forming a part of the inner end of the kerf 27. The forward portion of the block 24, and the corresponding portion of the forepart 16, are provided with complementary 105 locking members adapted to prevent forward endwise movement of the block and vertical and lateral movements of the forward portion thereof. Said members, as here shown, comprise an inclined socket 33 110

formed in the under side of the block, and an inclined dowel pin 34, attached to the forepart 16 and projecting from the block seat 17.

5 When the heel and foreparts are in the relative positions shown by full lines in Fig. 1, the rear end of the heel-part is at the maximum distance from the forward end of the forepart, the bottom edge of the hinge-plate 20 bearing on the bottom of the kerf 19, which acts as a stop to limit the relative swinging movements of the parts when the last is fully extended. The block 24 may now be applied, its locking member 33 being 10 placed upon the locking member 34, and the rear end portion of the block being swung downwardly until the end face 26 comes to a bearing on the abutment 14, the locking shoulder 30, at the same time swinging into 15 engagement with the locking shoulder 23. This operation causes the projections 28^a and 28^b of the locking-plate to enter the kerfs 15 and 19, respectively, and thus prevent lateral movement of the rear end portion of the block, the engagement of the shoulder 30 with the shoulder 23 at the same 20 time preventing a vertical movement of the rear end portion of the block.

It will now be seen that the block confined, 25 as described, and bearing closely against the abutment 14, acts as a strut to prevent relative swinging movements of the forepart and heel-part, the extended bearing of the end face 26 of the block against the abutment 14 of the heel-part, and the prevention of 30 the forward movement of the block by the locking member or dowel 34 rendering the last rigid and capable of withstanding the strains and pressures exerted on the last by 35 a leveling machine and other instrumentalities employed in the manufacture of a shoe on the last, the hinge pin 22 which connects the heel and foreparts being practically relieved from all strain. The locking-plate 28 40 pivoted to the instep block and having projections entering the kerfs in the heel and foreparts, and the locking shoulder engaging the locking shoulder in the heel-part, constitute a simple and effective means for locking 45 the rear end portion of the block against vertical and lateral displacement. Said locking-plate is displaceable to release the block, a portion of the plate projecting into a transverse orifice 36 in the block, so that a 50 tapering pin 37 (Fig. 4) inserted in said orifice is adapted to displace the locking-plate in the direction required to withdraw the shoulder 30 from engagement with the shoulder 23.

55 When the last is ready for use the abutment 14 on the heel-part, and the end face 26 on the instep block, are vertically arranged, or substantially at right angles with the longitudinal axis of the last, so that pressure 60 tending to collapse the last does not tend to

raise the block from its seat, but simply tends to force the block forward longitudinally, this tendency being resisted by the locking member 34.

I claim:

1. A last comprising a heel-part, a forepart hinged to the heel-part to permit longitudinal contraction and extension of the last, said parts being provided respectively with a vertical block abutment and a block seat, a detachable instep block having a bottom face adapted to bear on said seat, and a rear end face adapted to bear on said abutment when the last is extended, and means for detachably locking the block to the heel-part and fore-part, the block constituting a strut which prevents relative contracting movements of the heel and fore-parts. 70

2. A last comprising a heel-part, a forepart hinged to the heel-part to permit longitudinal contraction and extension of the last, said parts being provided respectively with a vertical block abutment and a block seat, a detachable instep block having a bottom face adapted to bear on said seat, and a rear end face adapted to bear on said abutment when the last is extended, complementary locking members at the forward portions of the block seat and block to prevent forward endwise movements of the block, and vertical and lateral movements of its forward portion, and complementary locking members at the rear end portion of the block and the corresponding portion of the last to prevent vertical and lateral movements of the rear portion of the block and maintain it in position to act as a strut which prevents relative contracting movements of the heel and fore-parts, one of the last-mentioned locking members being displaceable to release the block. 80

3. A last comprising a heel-part, a forepart hinged to the heel-part to permit longitudinal contraction and extension of the last, said parts being provided respectively with a vertical block abutment and a block seat, a detachable instep block having a bottom face adapted to bear on said seat, and a rear end face adapted to bear on said abutment when the last is extended, complementary locking members at the forward portions of the block seat and block to prevent forward endwise movements of the block, and vertical and lateral movements of its forward portion, and complementary locking members at the rear end portion of the block and the forward end portion of the heel-part to prevent vertical and lateral movements of the rear portion of the block, one of the last-mentioned locking members being displaceable to release the block. 100

4. A last comprising a heel-part, having at its forward end a recessed bearing face, and a substantially flat abutment overhanging said recessed face, a fore-part cut away 110

at its upper portion to form a block seat and having its rear end formed as a salient face fitting the recessed face of the heel-part, said heel and fore-parts being provided with registering kerfs in their meeting ends, one of said kerfs opening into the abutment, and the other into the block seat, a hinge plate attached to the heel part within the kerf therein and projecting into the kerf of the fore-part, said plate having a locking shoulder, a pivot-pin connecting the projecting portion of the hinge-plate with the fore-part, the said recessed and salient faces being formed to permit relative swinging movements of the fore and heel parts, a detachable instep block having a bottom face formed to fit said block seat, and a rear end face formed to bear on said abutment, said block having a kerf registering with the kerfs in the heel and fore-parts, and a spring-pressed locking plate pivoted to the rear end portion of the block within the kerf

therein and having projecting portions formed to enter the kerfs in the heel and fore-parts, and prevent lateral displacement 25 of the rear portion of the block, and a locking shoulder formed to engage the shoulder on the hinge-plate and prevent vertical displacement of the rear portion of the block, said locking-plate being displaceable to release the block, the forward portion of the block and the corresponding portion of the fore-part being provided with complementary locking members adapted to prevent forward endwise displacement of the block and 30 vertical and lateral displacement of the forward portion thereof.

In testimony whereof I have affixed my signature, in presence of two witnesses,

ALFRED LEONARD STROBERG.
